[57] CLAIM

The ornamental design for a hand held computer, as shown and described.

DESCRIPTION

FIG. 1 is a top perspective view of a hand held computer showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

FIG. 8 is a front elevational view of a second embodiment thereof wherein the only difference is in the display window.

FIG. 1.

FIG. 2.

FIG. 4.

FIG. 3.

FIG. 5.

FIG. 6.

FIG. 7.

FIG. 8.
